UNITED STATES PATENT OFFICE.

EMMONS M. DOWER, OF BRIDGEPORT, CONNECTICUT, ASSIGNOR TO THE IVES CORPORATION, OF BRIDGEPORT, CONNECTICUT, A CORPORATION OF CONNECTICUT.

DESIGN FOR A TOY CIRCUS WAGON.

Application filed October 19, 1927. Serial No. 23,793. Term of patent 14 years.

To all whom it may concern:

Be it known that I, EMMONS M. DOWER, a citizen of the United States, and a resident of Bridgeport, in the county of Fairfield and State of Connecticut, have invented a new, original, and ornamental Design for a Toy Circus Wagon, of which the following is a specification, reference being had to the accompanying drawing, forming a part thereof, and in which—

Fig. 1 is a rear perspective view of a toy circus wagon showing my new design; and
Fig. 2 is a front perspective view.

I claim:

The ornamental design for a toy circus wagon substantially as shown.

Signed at Bridgeport in the county of Fairfield and State of Connecticut this 30th day of September, 1927.

EMMONS M. DOWER.
